UNITED STATES PATENT OFFICE

RALPH H. BOLEN, OF ASHLAND, KENTUCKY, ASSIGNOR TO THE AMERICAN ROLLING MILL COMPANY, OF MIDDLETON, OHIO, A CORPORATION OF OHIO

LEAD LINED PICKLING TANK

Application filed October 30, 1928. Serial No. 316,030.

It is the broad object of my invention to provide a new construction for pickling tanks of the type in which a wooden tank body is interiorly lined with lead, or of analogous types, whereby the first cost may be lessened and the life greatly lengthened. Pickling tanks of this type give considerable trouble. When used, for example, in a spider pickler for iron or steel sheets, they must contain hot acid. Leakage occurs through the acid proof lining, and acid is splashed over the edges and runs down the outer walls of the tank. The tank parts are rapidly attacked; when acid gets down between the lining and the tank, the corrosion proceeds without check, and it is not generally possible to repair the tank body or insert a new part in place of a defective one without dismantling the entire assembly.

It is the object of my invention to provide a construction whereby the use of small bolts, nails, screws, dowels or carpentry joints, which for strength are dependent on fine and accurate fitting, has been avoided. It can readily be seen that in pickle tank construction the use of any of these features is undesirable due to their susceptibility to deterioration from the action of acid solutions, which from overflow, leakage, or fumes is always present in a picking plant. In this invention the individual members are joined and held securely in place with simple butt and shoulder joints (which maintain maximum sections of the framed timbers) and a minimum of external tie rods all of which are exposed so that it may individually be replaced without dismantling the tank and even without interrupting its use, and so that they may frequently be flushed with water, whereby their life may be greatly lengthened.

It is another object of my invention to provide an open work frame-work with spaces between the component timbers. This permits the acid which may leak through imperfections in the inner lining to drain away instead of seeping in between the timbers and lining and being held there. It permits the more ready location of leaks. Further it permits the flushing of the individual timbers with water to remove acid which may have

seeped through the lining or spilled over the sides.

These and other objects of my invention which will be pointed out hereinafter or will be apparent to one skilled in the art upon reading these specifications, I accomplish by that certain construction and arrangement of parts of which I shall now describe a preferred embodiment, reference being made to the drawings which form a part hereof.

In the drawings:

Figure 1 is a top plan view of one form of my tank.

Figure 2 is a side elevation thereof.

Figure 3 is an end elevation.

Figure 4 is an isometric view of a corner of my tank with the lead lining removed to show the framework construction.

It is to be understood that my construction is applicable to tanks of various types. The preferred embodiment which I shall now describe is a tank suitable for use in a spider pickler; but the shape or proportions shown are not a limitation upon my invention.

Reference to Figure 1 shows a top frame work composed of end members 2 and side members 1, the purposes of which are:

1. By means of the notched joints (9) Figure 4 to prevent the inward collapse of vertical end timbers 8 and side timbers 11, (when tank is empty).

2. Through four substantially exposed vertical tie rods 10, Figure 3 and Figure 4, and bottom stringers 6, to provide a means of vertically securing the tank together as a unit.

3. To provide a smooth regular surface to which the inner lead lining may be secured.

The end members 2 may be housed out at points 2A to receive the ends of side timbers 9 which are stepped as shown most clearly at 2b (Figure 4). Thus thru this step joint, side members (1) are held down by end members (2). End members 2 are in turn held down by means of tie rods (10) to the bottom stringers 6.

The bottom comprises timbers or slats 4 of suitably heavy construction held apart and interspaced by spacers 5, which will more particularly be described hereinafter.

The floor of the tank rests upon stringers 6 as shown in the several views. The ends of the timbers 4 are notched as is shown most clearly at 7 in Figure 4 to receive the ends of the timbers 8 which make up the end walls. These timbers stand vertically upon the notched ends of the floor timbers and are interspaced by spacers 5a of which there may be as many horizontal rows as the length 10 of the timbers makes advisable. Three rows are shown in Figure 3.

The top of timbers 8 are notched inwardly, and the top end member 2 is notched outwardly as at 9 (Figure 4). This construction 15 forms a joint between the top frame and the end walls. Tie rods 10 join the top frame and the stringers 6, binding together the end construction. But it will be clear that if these tie rods be loosened a little, the stringers 14, 14a, etc., removed, one or more of the end timbers 8 may be removed outwardly for replacement and repair. In use, in order to 20 resist the outward pressure of the hydrostatic head within the tank, means must be taken 25 to prevent such an outward movement of the timbers, and such means are hereinafter to be described.

The side walls are similar to the end walls in that they comprise upright timbers 11, in- 30 terspaced by rows of spacers 5b (Figure 2) and notched and fitted into the top side frame members 1, as has been described for the timbers 8. Since the row of timbers 11 forming a side wall falls above and parallel to the 35 outermost floor timber, I prefer to use as said outermost floor timber on either side, a timber 4a which is less in height than the other floor timbers 4. This, where the width of floor timbers and thickness of side timbers 40 is the same, is less expensive than notching both the outermost floor timber and all of the side timbers in a construction similar to the joint with the top side member 2. The latter construction may however be used if de- 45 sired. Or indeed any other type of joint between floor and side timbers may if desired be substituted for that which I have shown, and which has the two chief advantages of 50 economy and easy demountability. What has been said about the easy individual removability of the timbers 8 will apply also to the timbers 11.

Heavy side stringers 12 rest upon the supporting stringers 6 and lie parallel to and 55 outside of the outermost floor timbers 4a. The ends of the stringers 12 project beyond the floor proper, and tie rods 13 and 13a bind the whole into a unitary structure. Further the members 12 and 4a together with the 60 next one of the floor timbers 4 form a socket for the feet of the timbers 11, as is very clearly shown in Figure 4.

Other stringers 12a, 12b, etc. may be located 65 above and parallel to the stringers 12, and may be bound together by tie rods 13b, 13c,

etc. They may be graduated in size in proportion to the hydrostatic pressure which they must withstand. They must be thick enough to bear with even pressure throughout their length upon the timbers 11. Their function is to prevent the outward movement of these timbers which the pressure of the acid upon the lining tends to produce, and also to strengthen the tank framework in such other ways as will be quite obvious. 70 They may be supported by vertical timber struts 17 and 17a where desired; or they may be otherwise supported.

To prevent the outward movement of the end timbers 8, I provide stringers 14, 14a, etc. transverse to these timbers and tied with rods 15, 15a, etc. To prevent racking and provide stiffness, I may tie the timbers 12, 12a, etc. with diagonal tie rods, 16, 16a, etc. 80

It will be noticed that all of the tie rods are exposed. It is not necessary in my construction to run the rods through the length of the timbers nor to have them enclosed within the body of the walls. I have found that enclosed rods, instead of being protected 85 from acid attack, are more liable to it and have a shorter life than rods which are exposed and can be and are frequently flushed with water. The rods are preferably of acid 90 proof metal. They may be individually replaced without interfering with the service 95 of the tank.

The spacers 5, 5a, etc., may be of any material desired; but I prefer to make them of acid-proof stoneware. They have continuously to resist the pressure of the members and give rigidity to the sides; and any disintegration through acid attack or otherwise will loosen up the entire structure. Wooden 100 spacers may be used if desired; but thin wood is liable to more ready attack, and I prefer to use a substance which will not be attacked at all, so that the resistance of the timbers themselves will measure the repair-free life 105 of the tank.

An acid proof inner lining of continuous or membranous character is placed within the tank, and preferably jointed to the outside of the top frame. It is an advantage of 110 my construction that it permits the use of such a lining as lead; but it is not restricted to such a lining, and may equally well be used with other and thicker ones. Linings which have an insulating as well as an acid resist- 115 ant character may be used; or such a lining as may comprise courses of acid proof brick laid in a suitable cement. But a lining which is neither thick nor rigid is greatly to be preferred for many reasons; and the construction of my tank is especially adapted to 120 the use of a membranous lining which relies upon my frame-work for support. In a tank of the character described, I use a lining of C. P. lead, indicated at 18 in Figure 4. 125 When lined, my tank has a construction 130

in which each timber is exposed upon three sides. The spacers are not thick; but space the timbers sufficiently to ensure this result. In the embodiment I have described, they may 5 be, say, $\frac{1}{2}$ inch thick. Thus each timber may be flushed regularly with water, and the effect of acid leakage done away with or greatly minimized through much dilution. No attempt is made to secure a liquid-tight 10 connection between timbers and lining, so that the flushing will be more or less effective even behind the timbers. Again, when a leak occurs in the lining, the acid speedily drains away and is not impounded against the frame. 15 The nature and location of the leak can readily be determined, and the tank drained for a quick repair, whereas in a tight wooden tank construction, leakage will usually make itself evident after and through the process 20 of attacking the structure. And a repair, while stopping leakage, will not prevent the further disintegration of the wood from the acid which has escaped.

Modifications in my invention to adapt it to 25 various tank sizes and shapes may be made without departing from the spirit of my invention.

Having thus described my invention, what 30 I claim as new and desire to secure by Letters Patent is:—

1. In a pickling tank, the combination of a sheet lead lining and a framework to support said lining, said framework comprising interspaced members exposing said lining. 35

2. In a pickling tank, a lining and a framework to support said lining, said framework comprising timbers interspaced so that each timber is exposed substantially upon 40 three sides.

3. In a pickling tank a construction comprising separate bottom, side and end walls all comprising timbers and spacers therebetween whereby an open-work construction is effected, means for supporting said bottom, side and end walls in relationship, and a lining in said tank supported by said bottom, side and end walls and substantially exposed by said open-work construction. 45

4. In a tank construction, a bottom supporting separate side and end walls, said walls formed of timbers with interspaced spacers therebetween, means for holding said members in relationship, and a lining in said tank supported by said members. 55

5. In a tank construction, a bottom comprising timbers side by side with spacers therebetween, separate side and end walls comprising timbers side by side with spacers therebetween and means for holding said bottom, sides and end walls in assembly and in relationship, and a lining in said tank supported by said bottom, side and end walls and substantially exposed between said timbers. 60

6. In a tank construction, a bottom comprising timbers side by side with spacers therebetween, side and end walls comprising timbers side by side with spacers therebetween and means for holding said bottom, 70 sides and end walls in assembly and in relationship, said means comprising external stringers and substantially exposed tie rods. 75

7. In a tank construction a bottom comprising timbers, side by side with spacers therebetween, a lower portion about the edge of said bottom to receive the feet of side and end walls, side and end walls stepped in said portion and comprising timbers side by side vertically with spacers therebetween, said timbers notched inwardly at the top, a top frame notched outwardly to receive the tops of said timbers, whereby said timbers may be removed outwardly, and means for holding said side and end walls and said bottom 85 in assembly and relationship. 80

8. In a tank construction a bottom comprising timbers side by side with spacers therebetween, a lower portion about the edge of said bottom to receive the feet of side and end walls, side and end walls stepped in said portion and comprising timbers side by side vertically with spacers therebetween, said timbers notched inwardly at the top, a top frame notched outwardly to receive the tops 90 of said timbers, whereby said timbers may be removed outwardly, and means for holding said side and end walls and said bottom 95 in assembly and relationship, said means comprising horizontal side and end wall 100 stringers projecting beyond the sides and ends and tie rods substantially exposed and connecting said projecting ends. 105

9. In a tank construction a bottom comprising timbers side by side with spacers therebetween, a lower portion about the edge of said bottom to receive the feet of side and end walls, side and end walls stepped in said portion and comprising timbers side by side vertically with spacers therebetween, said timbers notched inwardly at the top, a top frame notched outwardly to receive the tops of said timbers, whereby said timbers may be removed outwardly, and means for holding said side and end walls and said bottom 110 in assembly and relationship, said means comprising horizontal side and end wall 115 stringers projecting beyond the sides and ends and tie rods substantially exposed and connecting said projecting ends, stringers supporting said bottom and tie rods connecting said stringers and said top frame. 120

10. In a tank construction a bottom comprising timbers side by side with spacers therebetween, a lower portion about the edge 125 of said bottom to receive the feet of side and end walls, side and end walls stepped in said portion and comprising timbers side by side vertically with spacers therebetween, said timbers notched inwardly at the top, a top 130

frame notched outwardly to receive the tops of said timbers, whereby said timbers may be removed outwardly, and means for holding said side and end walls and said bottom

5 in assembly and relationship, said means comprising horizontal side and end wall stringers projecting beyond the sides and ends and tie rods substantially exposed and connecting said projecting ends, stringers

10 supporting said bottom and tie rods connecting said stringers and said top frame and a lining within said construction of membranous character.
